Seeger & Shaffer,

Post flinger.

No. 98,196.

Patented Dec. 21, 1869.

United States Patent Office.

GEORGE SEEGER AND CHARLES H. SHAFFER, OF CLARK'S HILL,
INDIANA.

Letters Patent No. 98,196, dated December 21, 1869; antedated December 11, 1869.

IMPROVED POST-AUGER.

The Schedule referred to in these Letters Patent and making part of the same.

To all whom it may concern:

Be it known that we, GEORGE SEEGER and CHARLES H. SHAFFER, of Clark's Hill, in the county of Tippecanoe, and State of Indiana, have invented a new and improved Post-Hole Auger; and we do hereby declare that the following is a full, clear, and exact description of the construction and operation of the same, reference being had to the accompanying drawings, making a part of this specification, in which—

Figure 1 is a side view.

Figure 2 is a cross-section.

Figure 3, detached view of leg *l* and rack *m*.

Figure 4, section, showing the operation of the arm *e*.

This invention relates to a post-hole boring-apparatus, mounted upon a wheelbarrow; and

The invention consists in providing the barrow with legs, that may be either turned up out of the way, or adjusted at any required angle, so as to keep the barrow level when on uneven ground; also in an apparatus for cleansing the auger; also in a device for keeping an adjustable shaft temporarily in place.

In the drawings—

A A represent a frame-work, of the kind ordinarily employed for supporting and operating earth-augers, through the centre of which passes the auger-shaft *a*, which has a transverse spur-gear, *a'*, upon it, and a chain, *a''*, hooked into its top, and passing over sheaves, *b b*, in the top of the frame, and thence down to a windlass, *c*, on a shaft, *c*, placed crosswise of the main frame, and bearing near its opposite extremity a spur-gear, *c'*.

Parallel with this shaft is another shaft, *d*, on the other side of the frame-work, which shaft may be shifted lengthwise, so that while in one position, its small spur-gear, *d'*, engages with the gear *c'*, and thus sets in motion the windlass *c*, by which the auger is elevated; in another position the wheels *c''* and *d* are thrown out of gear, and the wheels *d''*, on the shaft *d* and *a'* on the drill, are thrown into gear, and the auger consequently rotated.

We provide a device for keeping the shaft *d* in this latter position as long as necessary, the same consisting of an arm, *e*, hung upon a pivot on one of the standards *A*, a little above the shaft, and at its lower end provided with a pin, *e'*, projecting backward, and intended to enter an orifice in the bearing of the shaft *d*, and to fit in a transverse groove, *d''*, in said shaft, and thus prevent the shaft from moving endwise.

The lower end of the arm *e* should be weighted, the more readily to accomplish this result.

To accomplish its ready extrication from the groove in the shaft, we hang upon the same pivot the pawl *h*, which has a finger, *h'*, on its under side, which finger bears upon a rib, *e''*, on the outside of the arm *e*, when the arm is engaged with the shaft *d*.

By pressing down upon the pawl *h*, the arm is easily thrown out, and the shaft *d* may be moved endwise again.

The shaft *d* is provided with a crank on each end, for the application of power.

On the under side of the barrow *B*, which supports the frame *A A*, there is an inverted hollow cone, *i*, through the centre of which the auger passes, which cone has two wings, *i' i'*, projecting one from each side.

If the cutting blades be drawn up against the wings *i' i'*, and rubbed against the same, their upper surfaces may be thereby cleaned, and the spaces between the blades may be cleared.

In one end of the barrow, we place a wheel, *k*, in suitable bearings, for the transportation of the apparatus.

When this is to be done, the legs *l l* are turned back out of the way, the legs being pivoted to the side-pieces of the barrow.

Curved racks *m m* are placed one on each leg, by means of which, and pins, the legs may be set at any angle which may be required in order to keep the barrow level, whether the ground be level or not.

In order to indicate whether the barrow be level or not, we suspend a plumb-line, *n*, to the top of the frame.

Having thus described our invention,

What we claim as new, and desire to secure by Letters Patent, is—

1. In combination with the barrow *B*, the pivoted legs *l* and curved rack *m*, as and for the purpose described.

2. The conical cleaner *i*, provided with the wings *i' i'*, as and for the purpose described.

3. The pivoted arm *e*, provided with the pin *e'*, in combination with the groove *d''* of the shaft *d*, as and for the purpose specified.

GEORGE SEEGER.

CHARLES H. SHAFFER.
